INVENTOR,
Thomas Vander Lugt Jr.
BY *Ottie Q. Earl*
Attorney.

UNITED STATES PATENT OFFICE

2,678,152

COLLAPSIBLE CARTON MEMBER

Thomas Vander Lugt, Jr., Kalamazoo, Mich., assignor to Sutherland Paper Company, Kalamazoo, Mich.

Application December 8, 1951, Serial No. 260,636

2 Claims. (Cl. 229—35)

1

This invention relates to improvements in a collapsible carton member.

The main objects of this invention are:

First, to provide a collapsible carton member or element in which the walls collapse upon the main or body panel and may be quickly erected by an outward pull on opposed collapsed walls.

Second, to provide a carton member of this character in which the walls are effectively locked in erected position and one in which there is no damaging strain upon the hinges or joints connecting the parts or the parts themselves when they are in collapsed position.

Third, to provide a collapsible carton member of this type which may be used as a tray or body member or as a cover member.

Objects relating to details and economies of the invention will appear from the description to follow. The invention is defined and pointed out in the claims.

A preferred embodiment of the invention is illustrated in the accompanying drawing, in which:

Fig. 1 is a perspective view of a carton member embodying my invention with the walls in erected position.

Fig. 2 is an enlarged fragmentary side elevational view.

Fig. 3 is a fragmentary perspective view illustrating the parts in partially erected position.

Fig. 4 is a fragmentary plan view of the collapsed carton member.

Fig. 5 is a fragmentary view of one corner of the blank in the flat or extended form, one corner portion only being illustrated, as the other corners are duplicates of the one illustrated.

My invention is well adapted for embodiment in a tray type of carton and has many uses as such. However it will be understood that the carton member illustrated may be used either as a body member or as a cover member. It will also be understood that I use the terms side and end walls in the specification and claims for convenience in description and that the shape or dimensions of the carton may be varied according to the particular use to which it is to be put.

The embodiment of my invention illustrated is formed of an integral blank cut and scored to form a main panel 1, side walls 2—2 hingedly connected to the main panel at 3, the hinge connections being formed by scoring of the blank. End walls 4—4 hingedly connected to the panel 1 at 5 and corner members 6 hingedly connected to the end edges of the end walls at 7. These corner members are diagonally scored for fold-

2

ing at 8, the diagonal scoring forming inner scoring segments 9 and outer corner segments 10. The hinging scores 8 are on an angle substantially less than 45° relative to the hinging connection 7 for the corner members of the end walls. The purpose of this will be apparent from the further description.

The corner flaps in this preferred embodiment are of less height than the walls and the edges 11 of the inner segments 9 are inwardly spaced relative to the hinging line 5 to the end walls to the panel 1 and are desirably at an angle thereto as is shown in the drawing (see Figs. 4 and 5).

The inner portions of the end edges of the side walls are cut away at 12 providing clearance for the parts when in folded position, that is, the edges 12 are spaced from the hinges of the end walls when the carton is collapsed. The portions at the outer sides of these cut away portions 12 constitute tongues 13 which project longitudinally of the side members. The inner segments 9 of the corner flaps are lapped upon and fixedly secured to the outer sides of the side walls preferably by adhesive as indicated by 14 in Fig. 4.

It will be noted that when the walls are collapsed as shown in Fig. 4 the edges 11 of the inner corner member segments and the cut away portions of the end edges 12 of the side walls are substantially spaced from the hinging score or connections 5 for the end wall panel 1. This allows the end walls to be collapsed flat upon the side walls without pinching or applying tearing or cramping or stress to the parts. The hinging scores 8 being at an angle relative to the hinging score 7 substantially less than 45° results in the end walls being inwardly inclined when in erected position as is best shown in Fig. 2 so that the tongues 13 on the side walls project through the slots 15 formed at the juncture of the corner flaps with the end walls and provides an effective interlock which holds the wall in erected position and without fracturing or tearing stress on any of the parts either when the carton is erected or collapsed.

I have found that positioning the hinging scores 8 at an angle of 43½° relative to the hinging scores of the corner flaps to the end walls secures the desired result for providing an effective interlock and permits the parts to be collapsed without rupturing or breaking stress. I desire to point out however that this angle may be considerably varied with satisfactory results.

I have illustrated and described my invention in a highly practical embodiment thereof. I have

not attempted to illustrate or describe certain modifications and adaptations which I contemplate as it is believed this disclosure will enable those skilled in the art to embody or adapt my invention as may be desired.

Having thus described my invention, what I claim as new and desire to secure by Letters Patent is:

1. A collapsible carton formed of an integral blank and comprising a main panel and side and end walls hingedly connected thereto, and corner members of less height than the side walls hingedly connected to the end edges of the end walls and diagonally scored providing inner and outer collapsibly foldable segments, the inner segments being lapped upon in side by side parallel relation to the outer sides of the side walls and fixedly secured in such side by side parallel relation in and between collapsed and erected positions of the carton, the carton in a collapsed position being disposed with the side walls in superimposed relation to the main panel and the end walls in superimposed relation to the end portions of the side walls, the diagonal hinging scores for the corner segment being at an angle of approximately $43\frac{1}{2}$ degrees relative to the hinging connections of the corner members to the end walls, the end edges of the inner segments of the corner members being spaced inwardly and inclined relative to the hinging scores for the end walls to the panel in said collapsed position of the carton, the lower edge portions of the end edges of the side walls being cut away and the upper end edge portions of the side walls constituting longitudinally extending tongues projecting outwardly beyond the cut away lower edge portions of said end edges, the end walls and corner flaps at the hinged junctures thereof having slots opening upwardly through their upper edges at their junctures and receiving said tongues when the carton is erected, the end walls in the erected carton being inclined inwardly, the end edges of the inner segments and side walls below said tongues being spaced inwardly from vertical planes coinciding with the hinged connections of the end walls to the panel to permit of said inward inclination of the end walls when the carton is erected, said tongues being movable along the inner sides of the end walls and automatically engaging in said slots as the end walls are moved from said collapsed position to an erected position, said tongues and end walls being

5 relatively flexible and flexing relative to each other prior to engagement of the tongues in said slots to permit of such movement of the tongues along the inner sides of the end walls and said automatic engagement of the tongues in the slots.

2. A collapsible carton formed of an integral blank comprising a main panel and side and end walls collapsibly hinged thereto, and corner members hingedly connected to the end edges of the end walls and diagonally scored providing inner and outer collapsibly foldable segments, the inner segments being lapped upon and in side by side parallel relation to the outer sides of the side walls and fixedly secured in such side by side parallel relation to said side walls in and between collapsed and erected positions of the carton, the carton being collapsible with the side walls over the main panel and with the end walls over the end portions of the side walls, the lower edge portions of the end edges of the side walls being cut away and the upper end edge portions of the side walls constituting longitudinally extending tongues projecting outwardly beyond the cut away lower edge portions of said end edges, the end walls and corner flaps at the junctures thereof having slots opening upwardly through their upper edges at their junctures and receiving said tongues when the carton is erected, said tongues being movable along the inner sides of the end walls as the end walls are moved from a collapsed position over the end portions of the side walls to an erected position when the tongues automatically engage in said slots, said tongues and end walls being relatively flexible to flex relative to each other during such movement of the tongues and end walls and for such automatic engagement of the tongues in the slots.
